DINNER PLATE

Frederick F. Errill, Tuckahoe, N. Y., assignor, by
mesne assignments, to Home Decorators, Inc.,
Newark, N. Y., a corporation of New York

Application June 26, 1951, Serial No. 15,662

Term of patent 14 years

(Cl. D44—15)

To all whom it may concern:

Be it known that I, Frederick F. Errill, a citizen of Great Britain and a resident of Tuckahoe, county of Westchester and State of New York, have invented a new, original, and ornamental Design for a Dinner Plate, of which the following is a specification, reference being had to the accompanying drawing, forming part thereof, in which:

Fig. 1 is a top plan view of a dinner plate showing my new design; and

Fig. 2 is a sectional view of the dinner plate of Fig. 1.

The floral ornamentation shown in Fig. 1 is continued around the entire periphery of the plate.

I claim:

The ornamental design for a dinner plate, as shown and described.

FREDERICK F. ERRILL.
